Sydney G. Prescott
ATTORNEY

UNITED STATES PATENT OFFICE

JOHN FREDRIK HALSTEAD, OF BROOKLYN, NEW YORK, ASSIGNOR TO INTERNATIONAL CIGAR MACHINERY COMPANY, A CORPORATION OF NEW JERSEY

CUTTING FILLER TOBACCO FOR CIGAR BUNCHES

Application filed May 12, 1928. Serial No. 277,302.

This invention relates to an improved method of, and apparatus for, cutting the filler tobacco for cigar bunches, and is particularly intended for cutting the bunch charges of cigars pointed at one end and blunt at the other, in cigar machines in which a stream of filler material is cut transversely, so that the same cut serves for the tuck end of one cigar and the head end of the next. In cigar machines of this type hitherto used, if the shape of the cutter was made so that there was the proper amount of material at the blunt end of the bunch, then there was more tobacco at the pointed end than required for said pointed end of the bunch, and in squeezing the bunch down to shape, an unevenly packed cigar having poor drawing qualities, would result. The main object of the present invention is to provide a method and apparatus for cutting the filler in machines of this type, so that in one cut across the stream of filler material, the proper amount of material will be provided at each end of a charge to properly form the differently shaped head and tuck ends of the cigar. Another object is to provide a method and apparatus for cutting cigar filler material which will insure evenly packed cigars, having the desired drawing qualities. With these and other objects not specifically mentioned in view, the invention consists of certain constructions and combinations which will be hereinafter fully described and then set forth in the appended claims.

In the accompanying drawings:

Figs. 1 and 2 show the forms of cigars that the improved method and apparatus is intended to produce;

Fig. 3 illustrates the proper distribution of material at the end of the charge;

Fig. 4 illustrates the distribution of material resulting from a cut made by the corrugated knife alone;

Fig. 5 illustrates how material is removed from one end of the charge shown in Fig. 4 to attain approximately the desired distribution of material, as shown in Fig. 3;

Fig. 6 is a diagrammatic illustration comparing the distribution of material at the

pointed end of the cigar attained in the shape shown in Fig. 3 and that shown in Fig. 5;

Fig. 7 is an elevation of the apparatus, according to the invention for carrying out the improved method; and

Fig. 8 is a plan view of the apparatus shown in Fig. 7.

Referring to the drawings, when cigars with a blunt head H and a tapered or pointed tuck end T, as shown in Fig. 1, or with a pointed head H and a blunt tuck end T, as shown in Fig. 2, are to be made in an automatic cigar machine, the charge of filler tobacco for rolling each bunch should have the filler tobacco near the ends thereof, distributed as shown in Fig. 3, where the end of the charge intended for the pointed end of the cigar is cut much deeper than that intended for the blunt end. Cut in this way, the tobacco roll formed from the charge will naturally assume the desired shape without requiring undue squeezing in the finishing process. In cigar machines of the type to which the invention is applied, the filler tobacco is fed in a continuous stream of the proper width for the thickness of the cigar to be made. Corrugated cuts spaced a bunch length apart are made across this stream, the convexities and concavities of the cuts being of the same depth, and those on one side of the cut forming the head end of the cigar and those on the other side of the cut forming the tuck end of the cigar. If the shape of this cutter is selected to form perfectly one end of the cigar, then there will be more or less tobacco than is required for the other and differently shaped end of the cigar, and in squeezing the bunch down to shape an unevenly packed and imperfect cigar will result.

The present method by which this difficulty is overcome consists in punching out holes spaced from the cut, as shown in Fig. 5, in the end of the charge to form the pointed end of the cigar. As shown in Fig. 6, the area cut out in this way is equal to the difference in the amount of material required to form the tuck and head ends of the cigar. The holes cut in the filler may be of any shape, but are preferably oval, as shown, and

are spaced from the cut in juxtaposition to the convexities of the cut.

Accordingly, in carrying the invention into effect, a stream of filler material is provided, 5 corrugated cuts each spaced a bunch length apart are made across said stream, and an amount of filler material approximately equal to the differences in the amount of material needed to form said tuck and head 10 ends is removed from the stream at a point spaced from the cuts. In the best mode of carrying out the method contemplated, this material removed is punched out from the stream of filler material. The apparatus 15 used in carrying the invention into effect comprises a knife having a corrugated edge for cutting the tobacco, means to remove selected portions of the tobacco at a point spaced from the cut, and mechanism mounting 20 said knife and means for reciprocation to operate on said tobacco. In the best constructions this apparatus also includes a plurality of punches. The means above referred to may be widely varied in construction 25 within the scope of the claims, for the particular machine selected to illustrate the invention is but one of many possible embodiments of the same. The invention therefore is not to be restricted to the precise 30 details of the structure shown and described.

The mechanism for cutting the charges in accordance with the improved method above described is shown in Figs. 7 and 8. A cross bar 10 is mounted for reciprocation on the 35 vertical shafts 11, sliding in bearings 12, secured to the cigar machine, these shafts being reciprocated from the cigar machine by suitable means not shown. On this cross bar is adjustably mounted a knife block 13, to 40 which is clamped the corrugated cutter or knife blade 14. For this purpose a clamp piece 15 is provided, clamping the knife blade to the knife block and also carrying in vertical holes therein the interchangeable 45 punches 16, held in place by set screws 17. These punches are arranged as shown in Figs. 7 and 8, with their cutting portions in the same horizontal plane as the knife edge and with each punch arranged on the same 50 side of the cutting edge and in juxtaposition to the concavities of said edge. The belt 18, forming part of the cigar machine and running over the pulley 19, conveys the stream of filler material to a table 20 having apertures 55 registering with the knife blade 14 and the punches 16. By means of these apertures the table serves as a ledger plate for the knife blade and punches. As the shafts 11 reciprocate, the cross bar 10 operates the 60 knife 14 and the punches to operate on said tobacco, thereby cutting the charge in one operation to the shape shown in Fig. 5, having the proper amount of material arranged at each end of the charge to roll a cigar at 65 the blunt and pointed ends without undue

squeezing. It will be clear that by obvious changes in the size and spacing of the punches, practically any difference in the amount of material in the head and tuck ends between that desired and that provided by the conventional corrugated cutter blade, can be punched out as a part of the cutting operation. 70

What is claimed is:

1. In cutting filler material for cigar bunches having different amounts of material in the tuck and head ends, the method which consists in providing a stream of filler material, making corrugated cuts across the same spaced a bunch length apart, and removing from the filler material at a point spaced 80 from the cuts an amount of material approximately equal to the difference in the amount of material needed to form said tuck and head ends. 85

2. In cutting filler material for cigar bunches having different amounts of material in the tuck and head ends, the method which consists in providing a stream of filler material, making corrugated cuts across the same 90 spaced a bunch length apart, and punching out from the filler material at a point spaced from the cuts an amount of material approximately equal to the difference in the amount of material needed to form said tuck and head ends. 95

3. In cutting filler material for cigar bunches having different amounts of material in the tuck and head ends, the method which consists in providing a stream of filler material, making corrugated cuts across the same 100 spaced a bunch length apart and punching out of holes in juxtaposition to the convexities of the corrugated cuts, an amount of material approximately equal to the difference in the amount of material needed to form said tuck and head ends. 105

4. In cutting filler material for cigar bunches having different amounts of material in the tuck and head ends, the method which 110 consists in providing a stream of material, making crooked cuts across the same spaced a bunch length apart, and removing from the filler material at a position spaced from the cuts an amount of material approximately 115 equal to the difference between the amounts of material needed to form said tuck and head ends. 120

5. Apparatus for preparing filler tobacco for cigar bunches, comprising a crooked 125 knife for cutting the tobacco, and associated means for removing selected portions of tobacco spaced from the cut. 130

6. Apparatus for preparing filler tobacco for cigar bunches, comprising a crooked knife for cutting the tobacco, and associated means for removing selected portions of tobacco spaced from the cut, said removing means including a series of punches. 135

7. Apparatus for preparing filler tobacco 140

for cigar bunches, comprising a crooked knife for cutting the tobacco, and associated means for removing selected portions of tobacco spaced from the cut, said knife being corrugated and said removing means including a series of punches arranged in juxtaposition to concavities of said knife.

8. Apparatus for preparing filler tobacco for cigar bunches, comprising a crooked knife for cutting the tobacco, and associated means for removing selected portions of tobacco spaced from the cut, and a reciprocating block carrying said knife and said removing means.

In testimony whereof, I have signed my name to this specification.

JOHN F. HALSTEAD.
